UNITED STATES PATENT OFFICE.

RAYMOND D. HIGHET, OF WHITE PLAINS, NEW YORK.

DESIGN FOR A TOY ANIMAL.

56,872.

Specification for Design.

Patented Jan. 4, 1921.

Application filed March 11, 1920. Serial No. 365,072. Term of patent 7 years.

To all whom it may concern:

Be it known that I, RAYMOND D. HIGHET, a citizen of the United States, residing at White Plains, in the county of Westchester and State of New York, have invented a new, original, and ornamental Design for a Toy Animal, of which the following is a specification, reference being had to the accompanying drawings, in which—

I claim:—

The ornamental design for a toy animal, as shown.

RAYMOND D. HIGHET.
